THREAD CLEANER BRACKET

Harry Sarfert, Philadelphia, and Arthur A. Arnold, Pottstown, Pa.

Application May 11, 1937, Serial No. 142,066

1 Claim. (Cl. 28—68)

The present invention relates to an improved bracket for mounting a thread cleaner and associated parts.

In the mounting of thread cleaners as heretofore practiced in the art little, if any, attention has been given to the operative relation of the cleaner to the bobbin and other associated parts so that devices for such purpose now in use require a number of thread guides which are generally spaced so far apart or so far from the cleaner that it is easy to lay the thread around the cleaner rather than through it. Furthermore such prior devices are more or less limited in use to a specific type of cleaner plates and are only suited to that particular type.

Some of the objects of the present invention are to provide an improved thread cleaner bracket and associated parts; to provide a thread cleaner supporting bracket wherein provision is made for quickly and accurately leading the thread to the spool or bobbin; to provide a thread cleaner supporting bracket wherein but one thread guide or rest is required; to provide a bracket construction wherein the thread cleaner parts are so located as to make it practically impossible for the operator to pass the thread around the cleaner instead of through it; to provide a novel thread rest so arranged and constructed that it can be repositioned at will to remove a worn or roughened surface thereon; and to provide other improvements as will hereinafter appear.

In the accompanying drawing Fig. 1 represents a perspective of a thread cleaner bracket embodying one form of the present invention; Fig. 2 represents a front elevation of the same; Fig. 3 represents a rear elevation showing the bracket mounted for use; Fig. 4 represents a plan of the bracket with the cleaner plates removed; Fig. 5 represents a section on line 5—5 of Fig. 2; and Fig. 6 represents an elevation in part section of a portion of a winding machine showing the device of the present invention in operative position.

Referring to the drawing one form of the present invention comprises a bracket 10 for supporting the cleaner plates 11 in operative position between the swift 12 which carries the thread to be cleaned and the bobbin 13 which winds the cleaned thread. In the present description reference is made to but a single unit of the machine comprising one swift 12, one set of cleaner plates 11, and one bobbin 13, though it will be understood in actual practice that a plurality of swifts 12 are mounted for independent rotation, a plurality of cleaner plate sets are fixed to the

reciprocable traverse bar 14, and a plurality of bobbins 13 are carried by the individual spindles 15 and caused to rotate by any well known mechanism.

The cleaner plates 11 are in the form of two flat metal strips provided with cleaning edges 16 arranged in opposed relation and spaced apart the required thousandths of an inch to provide the thread receiving slot 17. The spacing can be provided by the use of shims, welding of the base ends, by making the base part of one plate wider than the base part of the other plate, or by any other means, since the spacing of the plates forms no part of the present invention. As usual the free or outer ends of the plates 11 are respectively cut at an angle to form in assembled condition a V-notch to guide the thread in to cleaner slot 17.

For supporting the plates 11 in operative position the bracket 10 is recessed to receive a retaining block 18 having a groove 20 in one side thereof of the proper dimensions to snugly seat the plates 11 in edgewise relation. This block 18 is preferably made fast by screws 21 which enter the side wall of the bracket 10 against which the base portion of the plates 11 are in contact. A modified form of this construction contemplates casting the block 18 as an integral part of the bracket 10 and machining the groove 20. A set screw 22 enters the end of the block 18 to engage the outer edge of one of the plates 11, thereby clamping the two plates in operative position.

For supporting the thread on its way to the cleaner slot 17, the bracket 10 is provided with two lugs 23 arranged in upstanding relation to support a thread rest 24 in parallel and close proximity to the side of the plates 11 which faces the front of the machine. This rest 24 is preferably of porcelain and is in the form of a relatively short cylindrical rod, one end of which seats in a socket 25 in one of the lugs 23, while the other end enters a hole 26 through the other lug 23. This hole 26 is threaded to receive a locking screw 27 which fixes the rest 24 in a selected position. The lugs 23 serve as stops to prevent displacement of the thread at the ends of the rest 24, while should the rest 24 become worn or roughened along its line contact with the thread, the screw 27 can be loosened and the rest 24 turned to a position with a new line of contact with the thread 29.

In order to mount the bracket 10 on the traverse bar 14, a notch 28 is grooved longitudinally of the bottom of the bracket 10 and is of the required angular shape to conform to the usual

contour of the top of the traverse bar 14. Thus one face of the notch is longer than the other and in this instance is so located that when the bracket is mounted on the bar 14 the cleaner plates 11 will be at the rear of the bar while the rest 24 will be at the front. In this connection it should be noted that the horizontal plane of the rest 24 is slightly below the horizontal plane passing through the top of the cleaning slot 17 and since this slot entrance is well above the level of the bobbin, the thread is drawn angularly downward with no opportunity of becoming displaced. A groove 30 extends longitudinally of the upper face of the bracket 10 and serves to receive the spring pressed ends of the usual retaining clips 31 which are fastened to the traverse bar 14 at proper locations.

It will now be apparent that a complete unitary bracket has been devised wherein the parts are reduced to a minimum and the arrangement is such that the thread is effectively delivered to the bobbin. Also it should be noted that the cleaner parts and the rest are directly associated in a pre-determined manner such that the travel of the thread from one to the other is in a relatively short path and leaves the cleaner in a downwardly direction toward the bobbin whereby the thread is held with certainty in the cleaner slot. An

important advantage of the present construction is that the relation of the parts makes it practically impossible for the operator to lead the thread directly to the bobbin, instead of through the cleaner slot, thus ensuring all of the thread being subjected to a cleaning action. 5

While only a single form is shown in which this invention may be embodied, it is to be understood that the invention is not limited to any specific construction, but might be applied to various 10 forms without departing from the spirit of the invention or the scope of the appended claim.

Having thus described our invention, we claim:—

A device of the character described comprising 15 a thread cleaner bracket including a base adapted to seat on a traverse bar, said base being recessed at one side, a notched bar seated in said recess and forming with the base a groove in the top thereof, upstanding cleaner plates seated in 20 said groove and extending above the base, means for locking the plates in the groove, integral arms extending upwardly from the base from the side opposite the bar, and a guide rest supported by said arms and extending therebetween over which 25 a thread is guided to said plates.
